CLAMPING DEVICE

James Conohan, Boston, Mass.

Application June 23, 1941, Serial No. 399,323

11 Claims. (Cl. 114—226)

This invention relates to a clamping device to hold a rope to a thimble.

The principal object of my invention is to provide a simple mechanical clamping device that can easily and quickly be tightened to hold a rope fast to a thimble while it is being spliced or otherwise worked upon.

Another object is to so construct said clamping device that its cost of production is relatively small, that is durable, and that is adapted for use with various sizes of thimbles and ropes.

A further object is to provide an operable construction of said device so that the clamping member that holds the rope fast at one side of the thimble can be completely tightened independently of the other clamping member.

The foregoing and other objects which will appear as the nature of the invention is better understood, may be accomplished by a construction, combination and operative arrangement of parts such as is disclosed by the drawing and specification. The nature of the invention is such as to render it susceptible to various changes and modifications, and, therefore, I am not to be limited to said disclosure; but am entitled to all such changes therefrom as fall within the scope of my claims.

In the drawing:

Figure 1 is a front elevational view showing my clamping device holding a rope fast on a thimble.

Figure 2 is a front elevational view showing a modified form of my clamping device holding a rope fast on a thimble.

Figure 3 is a sectional view taken on the line 3—3 of Figure 1.

Figure 4 is a front elevational view; partly in section, showing my clamping device holding a rope on a thimble with a spacer member in the opening in said thimble to thereby keep said device higher upon said thimble.

As illustrated, my clamping device has two U-shaped members 10 and 11 each embodying a pair of arms 10a and 11a spaced apart, and a web 10b and 11b connecting said pair of arms together. At their open or free end portion there are holes 14 extending through said arms 10a and 11a, said holes 14 in the pair of said arms of each said U-shaped member being in alignment so that a bolt B may extend through both of them. It will be observed that said arms 10a of said member 10 are nearer together than the said arms 11a of the said member 11, thereby permitting said arms 10a to extend into the space between said arms 11a, whereby the two pairs of said arms overlap each other. This enables a single said bolt B or other form of pin member to extend through said four holes 14, first extending through said arm 11a then through said two arms 10a and then through the other said

arm 11a, thus holding the end portions of the arms of both said members 10 and 11 in position opposite the opening in a rope thimble T which has a channel C in its outer surface.

5 Said connecting webs 10b and 11b of said U-shaped members 10 and 11 each have a screw-threaded aperture 16 therein and a set screw 17 makes screw-threaded engagement therewith and extends therethrough. Fastened at the inner end of said set screw 17 is a saddle 19 which preferably has a groove in the face surface thereof and which is wedge-shaped so that it will bear more evenly against the rope R that extends around said thimble T. When said screw 17 is tightened said saddle 19 bears against said rope R and holds it firmly in said channel C. It will be observed that said screw 17 can be moved independently of all other moving parts so that the rope R on one side of said thimble T can be clamped fast thereto irrespective of what is done to said rope R at the other side of said thimble.

When it is desired to hold my clamping device at a predetermined point on said thimble T I provide an open spacer member 20 that is adapted to fit in the lower part of the opening in said thimble. Said bolt B extends through the opening in said insert member 20, and thus my device is held in the desired position in said thimble T.

In Figure 2 of the drawing I show a modified form of said U-shaped members 10 and 11 in which said arms 10a and 11a have extended portions 22 which extend downwardly at an angle to the remainder of said arm. Said extensions 22 have said holes 14 therein and they enable the user to keep my clamping device farther up on said thimble T and thus keep it out of the way of a vise that is used to hold a thimble should that be necessary.

40 My invention is adapted to hold fabric or wire rope or cables generally to said thimble T. When said bolt B extends through said holes 14 in said members 10 and 11 and is kept in place by a nut or otherwise, and when said set screws 17 are tightened to thereby force said saddles 19 against said rope R, the clamping operation is complete and is all that is needed to hold said rope in position while it is being spliced or otherwise worked upon.

50 What I claim is:

1. A clamping device to hold rope to a thimble comprising two U-shaped members each embodying two arms and a connecting web, the said arms of one said member being spaced apart a shorter distance than the arms of the other said member whereby they may be inserted between said arms of the latter said member, said arms of each said member having holes therein at their outer end portions that are in alignment whereby said members can be held

together by a pin member extending through said four holes, said webs each having a threaded aperture therein and each having a screw-threaded member screw-threadedly extending into said aperture.

2. A clamping device to hold rope to a thimble comprising two U-shaped members each embodying two arms and a connecting web, the said arms of one said member being spaced apart a shorter distance than the arms of the other said member whereby they may be inserted between said arms of the latter said member, said arms of each said member having holes therein at their outer end portions that are in alinement whereby said members can be held together by a pin member extending through said four holes, said webs each having a threaded aperture therein and each having a screw-threaded member screw-threadedly extending into said aperture, and a saddle member fastened to each said screw-threaded member at the inner end thereof.

3. A clamping device to hold rope to a thimble comprising two U-shaped members each embodying two arms and a connecting web, the said arms of one said member being spaced apart a shorter distance than the arms of the other said member whereby they may be inserted between said arms of the latter said member, said arms of each said member having holes therein at their outer end portions that are in alinement whereby said members can be held together by a pin member extending through said four holes, independent clamping member movably mounted on said U-shaped members each adapted to be moved to clamping position independently of the other.

4. A clamping device to hold rope to a thimble comprising two U-shaped members each embodying two arms and a connecting web, the said arms of one said member being spaced apart a shorter distance than the arms of the other said member whereby they may be inserted between said arms of the latter said member, each said arm having an extension portion extending downwardly from the adjoining portion of said arm when said device is in clamping position and having holes therein that are in alinement whereby said members can be held together by a pin member extending through said four holes, said webs each having a threaded aperture therein and each having a screw-threaded member screw-threadedly extending into said aperture.

5. A clamping device to hold rope to a thimble comprising two U-shaped members each embodying two arms and a connecting web, the said arms of one said member being spaced apart a shorter distance than the arms of the other said member whereby they may be inserted between said arms of the latter said member, each said arm having an extension portion extending angularly from the adjoining portion of said arm and having holes therein that are in alinement whereby said members can be held together by a pin member extending through said four holes, said webs each having a threaded aperture therein that is higher than said holes when said device is in clamping position, and each having a screw-threaded member screw-threadedly extending into said aperture.

6. A clamping device to hold rope to a thimble comprising two U-shaped members each embodying two arms and a connecting web, the said

arms of one said member being spaced apart a shorter distance than the arms of the other said member whereby they may be inserted between said arms of the latter said member, each said arm having an extension portion extending at an acute angle from the adjoining portion of said arm and having holes therein that are in alinement whereby said members can be held together by a pin member extending through said four holes, said members each having an aperture therein and each having a member extending into and adapted to extend through said aperture to hold a rope to a thimble.

7. A U-shaped clamping member having provision to receive clamping means, said member embodying two arms, a web between and connecting said arms, and extension members extending from said arms at an angle thereto.

8. A U-shaped clamping member adapted to cooperate with clamping means, said member embodying two arms spaced apart, a web between and connecting said arms, and extension members extending from said arms at an angle thereto, said extension members having holes therein in alinement with each other.

9. A U-shaped clamping member embodying two arms, a web between and connecting said arms, and extension members extending from said arms downwardly when said member is in clamping position and having holes therein, said web having a threaded aperture which is higher than said holes when said member is in clamping position.

10. A clamping device in combination with a thimble and a rope extending around said thimble, said device comprising two U-shaped members each embodying two arms and a connecting web, the said arms of one said member being spaced apart a shorter distance than the arms of the other said member whereby they may be inserted between said arms of the latter said member, said arms having holes therein in alinement with each other, said arms extending across opposite sides of said thimble and overlapping each other so that all said holes are in alinement, a pin member extending through said holes, said webs each having a threaded aperture therein and a screw member screw-threadedly extending into and beyond said aperture and against said rope.

11. A clamping device in combination with a thimble and a rope extending around said thimble, said device comprising two U-shaped members each embodying two arms and a connecting web, the said arms of one said member being spaced apart a shorter distance than the arms of the other said member whereby they may be inserted between said arms of the latter said member, said arms embodying extensions integral with and extending downwardly therefrom when said device is in clamping position and having holes therein in alinement with each other, said arms extending across opposite sides of said thimble and overlapping each other so that all said holes are in alinement, a pin member extending through said holes, said webs each having a threaded aperture therein and a screw member screw-threadedly extending into and beyond said aperture and against said rope, the center of said aperture being higher than the center of said holes when said device is in clamping position.

JAMES CONOHAN.
